FITZ WILLIAM SARGENT, OF MAHWAH, NEW JERSEY, ASSIGNEE TO AMERICAN BRAKE SHOE & FOUNDRY COMPANY, OF MAHWAH, NEW JERSEY, A CORPORATION OF NEW JERSEY.

REINFORCING-BACK FOR BRAKE-SHOES.

1,158,563.

Specification of Letters Patent.

Patented Nov. 2, 1915.

Application filed September 13, 1915. Serial No. 56,854.

To all whom it may concern:

Be it known that I, FITZ WILLIAM SARGENT, a citizen of the United States, and a resident of Mahwah, in the county of Bergen and State of New Jersey, have made and invented certain new and useful Improvements in Reinforcing-Backs for Brake-Shoes, of which the following is a specification.

10 This invention relates to reinforcing backs for brake shoes, and concerns in particular that type of back wherein the looped lug portion is provided with reinforcing and bracing means, so as to prevent the spreading and opening up thereof.

An object of the present invention is to provide improved means for bracing this lug portion of the back, and to accomplish the same in an economical manner. In 20 bracing the lug portion and reinforcing back, it has, heretofore, been the practice to provide a separate tie-plate which extends beneath the lug of the back and is secured by rivets or other suitable means to the sides of 25 the lug. This provision of a separate tie-plate, in addition to requiring considerably more material than ordinarily embodied in a brake shoe back, also requires that the tie-plate be secured and anchored to the back at 30 both of its ends.

A material saving of metal is effected in the present invention by forming the tie-plate from a portion of the back itself, the removal of which tie-plate defines an 35 opening, through which the body metal of the shoe flows, and which materially aids in the anchorage thereof. In addition, but one joint is required for the securement and anchorage of the tie-plate to the back.

40 A further object is to provide a reinforcing back with a looped lug, and with a tie-plate formed integral therewith, the tie-plate being bent beneath the open lug, and up and around the remote portion of the 45 back, so that it is rigidly and permanently anchored thereto, and does not depend upon the cast metal of the body of the shoe for its securement.

Other objects and advantages will appear 50 as the description proceeds, wherein it is to be understood, that changes in the precise embodiment of my invention, can be made within the scope of what is claimed, without departing from the spirit thereof.

The preferred embodiment of my invention is disclosed in the accompanying drawings, wherein:

Figure 1 is a view in plan of the blank from which my improved reinforcing back is formed; Fig. 2 is a view in longitudinal vertical section of the reinforcing back embodying the characteristic features of my invention; Fig. 3 is a fragmental view in perspective of the same, and on an enlarged scale; Fig. 4 is a view in transverse vertical section of a brake shoe with my novel reinforcing back embodied therein; and—Fig. 5 is a view in side section of a somewhat slightly modified form of reinforcing back, the modification residing in the securement 70 of the free end of the tie-plate to the back.

Referring specifically to the several views, the blank, illustrated in Fig. 1, is formed from an oblong plate 5, the central and lug-forming portion 6 of which, is provided 75 with the spaced and symmetrically arranged openings 8. To one side of the lug portion 6, is provided the U-shaped slot 10, the same being so located as to define a tongue 11, the free portion of which, is located remote 80 from the lug portion 6 of the blank. Upon the opposite side of the lug portion, with regard to the tongue 11, is provided the opening 9, which, in connection with the opening defined by the removal of the 85 tongue 11, as hereinafter described, provided the usual openings, into which the metal of the body of the shoe may flow for its secure anchorage.

The blank, as above outlined, is looped or bridged at its central portion to form the outwardly looped and integral lug 7, the openings 8 in which, are adapted to receive the usual shoe attaching key. The tongue 11 is bent downwardly beneath the plate 5, 95 and across the open lug 7, and, as thus located, forms an integral tie-plate 12, the one extremity of which is formed integral with the back adjacent the one side of the lug and the remote extremity 13 of which is 100 bent up through the opening 9, and around the edge thereof, so as to become securely and permanently anchored thereto, the securement and anchorage of which does not depend upon the cast metal of the body of 105 the shoe, although it may be, to some extent, supplemented thereby. The over lapping end 13 of the tie-plate is removed a suffi-

cient distance from the lug, so as to not interfere with the attachment of the shoe to the break head.

The reinforcing back, as thus constituted, is placed within the mold and the wearing metal of the body is cast thereon. The body metal of the shoe lying directly beneath the open lug 7 is reinforced by the tie-plate 12, and the back is held against spreading and the lug opening up by the same means.

The somewhat modified form of reinforcing back, illustrated in Fig. 5, is similar to the foregoing with the exception that the free extremity of the integral tie-plate 12' 15 is not directly connected to the back, but is secured and anchored thereto by the rivet 14, this rivet being formed from the cast metal of the body of the shoe flowing up through the alined openings 15, with which 20 the tie-plate and the reinforcing back are provided.

What I claim is:—

1. A reinforcing back for brake shoes with an open looped lug, and a tie-plate 25 formed integral with said back, extending across said lug and permanently anchored to said back.

2. A reinforcing back for brake shoes with a looped lug, and a tie-plate formed 30 integral with said back, and extending beneath said looped lug, the free extremity of

said tie-plate permanently secured to said back.

3. A reinforcing back for brake shoes with an outwardly formed lug, and a tie-plate 35 connected to and formed integral with said back, adjacent one side of said lug, said tie-plate being bent beneath and extending across to the opposite side of said lug and permanently anchored thereto. 40

4. A reinforcing back for brake shoes formed with an outwardly looped lug, a tie-plate formed integral with said back, and projecting across said lug with the free extremity thereof bent into engagement and 45 interlocking with said back.

5. A brake shoe comprising a reinforcing back with an outwardly looped lug, a tie-plate formed integral with said back and projecting across said lug and anchored to 50 the remote side thereof, and a body anchored to said reinforcing back and tie-plate, with the metal thereof extending into the opening defined by the formation of said tie-plate. 55

Signed at Mahwah, in the county of Bergen and State of New Jersey, this 10th day of September A. D. 1915.

FITZ WILLIAM SARGENT.
